FREQUENCY SHIFT RECEIVER

John C. E. Mitchell, Montreal, Quebec, Canada,
assignor to Radio Corporation of America, a
corporation of Delaware

Application May 16, 1946, Serial No. 670,085

5 Claims. (Cl. 250—8)

1

This application discloses an improved receiver for frequency shift telegraphy, facsimile and similar signals.

In order to reduce signal distortion, signal mutilation and signal dropout resulting from multipath transmission, etc., on telegraphy, facsimile and similar signals, frequency shift systems known in the prior art usually make use of multiple receivers in space diversity systems and in some cases of multiple receivers in frequency diversity as well as space diversity. See for example Lyons U. S. application Serial #578,877, filed February 20, 1945, and Lyons U. S. application Serial #648,965, filed February 20, 1946.

These known systems are quite complicated and are of considerable original cost and quite expensive to keep in operation. The primary object of my invention is to provide a receiver of frequency shift signals which is simple in nature and of relatively low cost and yet provides an output for recording or similar purposes which is sufficiently free of signal distortion, signal mutilation and signal dropout to be relied on for communication purposes.

Briefly I attain this object by provision of a new and improved tunable receiver comprising selective circuits of sufficient band width to permit local oscillator or transmitter drift within reasonable limits, thus rendering unnecessary automatic frequency control circuits. The improved receiver includes as a novel combination, an amplifying current amplitude limiter which improves the signal to noise ratio and increases the signal strength with an oscillator locked in by the limiting amplifier which oscillator repeats and further amplifies and shapes the signal pulses to provide for detection purposes full signal output when signal input of reasonable strength and quality is received. The novel combination also provides means for using signal where mark or space is mutilated and includes with the amplifying limiter locked oscillator, a frequency discriminator and detector having a characteristic of sufficient width to provide linear output over the frequency shift range.

The detector output controls a first locking circuit which in turn controls a locking circuit such as described in Cohoon U. S. application Serial No. 649,343, filed February 21, 1946, now abandoned.

The receiver of the present invention is to be used for reception of frequency shift signals which terminate in a given condition, for example, in mark condition, and is to supply said signals to recording apparatus such as a tele-

2

typewriter arranged to start operation on the reception of space. The locking circuits have two conditions of stability and in practice may not be left in mark condition when signaling is terminated, or, when no carrier signal is being received the locking circuits may be tripped to space condition. A further object of my invention is to provide an improved circuit arrangement for tripping the locking circuits to the mark signal condition in the absence of a received carrier signal if the system is not already in such condition. Briefly this object is accomplished by utilizing a potential developed in the current amplitude limiter circuit which is substantially linearly related to the received carrier strength for producing in the locking circuit the same result as would the appearance of a mark signal. This means is not to be confused with the trigger or locking circuit restoring means of my U. S. application Serial No. 659,477, filed April 4, 1946. The Locking circuit restoring means operates to return the locking circuit to mark condition if tripped to space condition by a noise pulse. The present means maintains the locking circuit in mark condition when there is no signal carrier being received.

The manner in which the above objects and other objects the nature of which will appear in detail hereinafter are attained will now be described in detail. In this description reference will be made to the attached drawings wherein

Fig. 1 illustrates schematically and by block diagram a frequency shift receiver such as, for example, one receiver of the diversity systems referred to hereinbefore. Applicant makes no claim to the receiver of Fig. 1.

Figs. 2a, 2b and 2c are curves or voltage diagrams illustrating operation of the arrangement of Fig. 1 and also illustrating the manner in which multipath transmission or fading or noise affects the signal in such a receiver thereby illustrating the need of my invention.

Fig. 3 illustrates schematically and by block diagram a frequency shift telegraphy or facsimile receiver arranged in accordance with my invention.

Fig. 4 illustrates details of the current limiting amplifier and locked oscillator of the arrangement of Fig. 3.

Figs. 5a and 5b illustrate by curves the operation of the limiting amplifier locked-in oscillator.

Figs. 6a, 6b, 6c and 6d are voltage diagrams illustrating the manner in which noise is reduced by the use of my limiting amplifier locked-in oscillator.

Figs. 7a, 7b and 7c illustrate by voltage diagram

the output derived from the limiting amplifier locked-in oscillator and locking circuit.

Fig. 8 illustrates by circuit element and circuit element connections a receiver arranged in accordance with my invention and including the novel combination of the current amplitude limiter locked-in oscillator, linear detector and the locking circuits controlled thereby with my improved squelch circuit actuated by the potential drop in the amplifying limiter for keeping the locking circuit in the mark condition in the absence of received signal.

Known frequency shift receivers used singly or in space diversity and/or frequency diversity may be as illustrated in Fig. 1 and may include the following features. A means of signal selectivity such as found in the tuned circuits of a radio frequency amplifier 2, and in particular in the tuned circuits of the intermediate frequency amplifier 4 of a conventional amplitude modulation receiver, followed by a conventional limiter 10, and a discriminating network 13 and detector which is a modification of the discriminator and detector illustrated in Seeley Patent #2,121,103. A large capacitor 12 couples the discriminator output to the input of a signal amplifier 14. The purpose of this large output coupling capacitor 12 has been described in detail in the abandoned Peterson U. S. application Serial #630,428, filed November 7, 1945, and is to permit signal drift from the center frequency without changing the polarity or sense of polarity of the signal pulses. The signal pulses are then filtered in unit 16 and actuate double locking circuits 18 and 20 of the type described herein and in the abandoned Cohoon U. S. application Serial #649,343, filed February 21, 1946, or in Schock et al. U. S. application Serial #632,978, filed December 5, 1945. A large condenser 17 having the same purpose as the condenser 12 is in the coupling between units 16 and 18. The locking circuits control a teletypewriter, facsimile recorder or similar recording device.

The practical operation of this system requires the following operating conditions:

a. In the absence of automatic frequency control means selectivity must be such that the pass band is sufficiently wide to allow for local oscillator drift in the receiver and oscillator drift in the transmitter. This means that the effective bandwidth must be greater than that required to pass the two signal frequencies (mark and space) and their side bands. (Usually two or three times as wide.)

b. Adequate amplification must be used ahead of the limiter in all of the single frequency shift systems. This is of the utmost importance and is so because during selective fading one of the frequencies is generally much weaker than the other, as much as 20 to 30 db. Without the additional amplification to insure saturation of the weaker signal, about 40 db, operation of a single receiver is unsatisfactory. The stronger frequency appears to provide limiter saturation and thereby masks lack of limiting on the weaker frequency. Slow AVC is also a disadvantage in this respect and in most receivers that I have come across the AVC cannot be used because it establishes the gain of the receiver on the strength of the stronger frequency. These points are relatively unimportant in the diversity systems because the diversity systems are arranged to use only the stronger instantaneous frequency whereas in the single receiver the weaker fre-

quency must be used in conjunction with the stronger frequency.

c. That such selectivity be provided before final limiting.

d. The linear portion of the center of the discriminator curve must be as wide as that required in (a).

e. The insertion of a large coupling condenser 12 between the discriminator output and the input to the locking circuit to allow the signal to drift from the center of the discriminator curve and still retain its sense or polarity.

f. That the coupling condenser 17 in conjunction with the grid resistor 19 and the input grid of the locking circuit in unit 18 act as a direct current restoring device for detected (discriminator) signal voltage. The major advantages of this system are:

1. Drift of the intermediate frequency signal may be accommodated within the pass band of the receiving system.

2. The system operates on transient voltages from the discriminator and consequently it is not necessary that the whole area of the received signal be present but only that the potential difference between successive signal characters exist.

The system illustrated in Fig. 1 and similar systems have certain disadvantages. Interfering signal or noise removed from the wanted signals by an appreciable frequency difference are able to create an appreciable number of errors. This is due in part at least to the use of wide band pass circuits necessary in the absence of automatic frequency control to allow for carrier drift. The manner in which the errors are created is illustrated in Figs. 2a, 2b and 2c. In Fig. 2a the output of a discriminator is represented and includes as well as the wanted signal three points at which the interfering signal has saturated the limiter and produced unwanted output. These points are shown at A, B and C. Fig. 2b illustrates the signal as originally transmitted before the same has been subjected to interference and the noise resulting therefrom. Fig. 2c represents the resultant output from the system which might be supplied from the locking circuit in unit 20 and includes the errors introduced by interference or noise. These errors are shown by shaded lines in Fig. 2c.

An object of the present invention is to provide a single simple receiver for frequency shift and similar signals wherein the effects of interference of the nature described above are substantially reduced and so effectively eliminated that good results are obtained by use of the same.

A second object of the present invention is to provide a simple and relatively inexpensive receiver for frequency shift and similar signals wherein the effects of interference of the nature described above are reduced and which receiver does not rely on space diversity effects to reduce the interference. Because intelligence is transmitted on two frequencies ($\pm FS$) a form of frequency diversity is involved if one considers that only one of the two frequencies is quite often all that is required to produce a satisfactory output character.

An additional object of the present invention is to provide a simple and relatively inexpensive receiver for frequency shift and similar signals wherein the effects of interference of the nature described above are reduced and which receiver does not rely on the use of automatic frequency control connections for tuning purposes.

A more detailed object of the present invention is to provide a system for frequency shift telegraphy and similar signals comprising a single receiver in a simple circuit having in general the makeup of the prior circuit of Fig. 1 but including means for eliminating the disadvantages mentioned above and in particular output distortion caused by interfering signals or noise resulting from multipath transmission. An embodiment of my receiver for attaining this object is illustrated in Fig. 3. In Fig. 3 by an improved combination of means, reduction of the effects of interference is accomplished and the novel combination of means does not unduly add to or complicate the receiver system. Moreover it allows reception of signals under interference conditions which would render it impossible to receive signals on known receivers which do not make use of diversity effects, and yet it retains the advantages of a band pass two to three times the width of the frequency shift in accordance with signals. My novel receiver then has all of the desirable features enumerated above in the discussion of Fig. 1 and none of the undesirable features, and yet does not involve automatic frequency control circuits or receivers in diversity. The receiver of my invention is essentially the same as that described and illustrated in Fig. 1 except for the provision of more gain in the stages preceding the limiter and the introduction of a locked oscillator 11, interposed between the current amplitude limiter 10 and the frequency discriminator and detector 13, as illustrated in Figs. 3 and 4 of the drawings. Any current amplifying limiter having the desired characteristics may be used but preferably I make use of an arrangement as illustrated in Fig. 4 and Fig. 8 of the drawings.

The frequency shifted signal is picked up and amplified and converted to a lower frequency in units 2 and 4, Fig. 3. The output of unit 2 which may be at any intermediate frequency $IF \pm FS$, where FS is the frequency shift, is fed to the first stage of an IF amplifier 4, the last stage of which may include tube V1 Fig. 4 coupled in a tuned amplifier circuit. This circuit includes an input transformer (not shown) tuned to pass a band of frequencies considerably greater than $IF \pm FS$. The anode of tube V1 is connected to an inductance L_1 and condenser C_1 parallel tuned to the frequency IF . The gain of the stages preceding the amplitude limiter V2 is stepped up until limiting takes place on mark and space frequencies irrespective of their relative strengths. The current amplitude limiter and locked-in oscillator comprises a limiter tube V2 having its control grid GL coupled by a resistor R_1 and coupling condenser C_2 to the tuned anode circuit C_1 , L_1 of the intermediate frequency amplifier. The anode AL of the limiter tube V2 is connected with a potentiometer resistor R_2 and by a second resistance R_3 to the positive terminal of a source B_3 of direct current potential. Potential for the screen grid of the limiter is supplied through a potential dropping condenser R_7 . The tap point on the potentiometer R_2 is coupled by condenser C_5 over a grid biasing resistor R_4 to the control electrode GO of a locked in oscillator including tube V3. The tube V3 has its screening electrode and a second control grid regeneratively coupled by transformer T_2 including inductance L_2 coupled to the parallel tuned circuit comprising inductance L_3 and condenser C_1 . Direct current potential for the screen grid is supplied through the inductance L_3 while biasing po-

tential for the third grid is supplied by resistor R_5 . The grid alternating current circuit includes a coupling condenser C_6 and a resistor R_6 . The anode AO of the tube V3 is coupled to the primary winding L_4 of a transformer T_3 in a modified Seeley discriminator and detector system. The primary inductance L_4 is in parallel with tuning condenser C_8 . The anode AO is also substantially directly coupled to the diodes in parallel by a separate lead 30 running from the anode to the tuning and direct current blocking condensers C_{10} and C_{11} .

The operation of the system is as follows. Voltage from the intermediate frequency amplifier 15 which may be of the order of 400 kc. is developed across the circuit L_1 , C_1 which is parallel resonant to the said intermediate frequency. This intermediate frequency voltage is fed through the coupling circuits C_2 , R_1 to the control grid GL of the limiter tube V2. Capacitor C_2 and resistor R_1 comprise a short time constant grid input circuit (say of the order of 10 to 18 microseconds), and this in combination with a lower than normal screen voltage supplied through the resistor R_7 and in cooperation with the IF bypass condenser C_3 insures operation of the tube V2 as a conventional current amplitude limiter. In this limiter the tube V2 is biased beyond cutoff by negative excursions 20 of the alternating current, thereby limiting the peak amplitude of the currents in the negative direction. Due to the low screen grid potential supplied by resistor R_7 and the relation thereto of the magnitude of the driving currents the 25 tube is driven beyond saturation on the positive cycles to thereby accomplish current peak amplitude limiting on the positive peaks.

Voltage at the intermediate frequency which has been limited appears across the potentiometer R_2 , this voltage being of a constant alternating current magnitude for varying amplitudes of intermediate frequency signal applied to the input of tube V2, provided the signal is greater than a selected critical value, say 3 or 4 volts at the 30 grid of the limiter. That is, limiting begins to take place with this arrangement of tube and components at 3 to 4 R. M. S. IF signal volts on the input grid of V2. Voltage from the potentiometer resistance R_2 is coupled through coupling 35 and blocking condenser C_5 and grid leak resistor R_4 to the control grid GO of the locked oscillator including tube V3. The capacitor C_5 and resistor R_4 also provide a short time grid input circuit in so far as the characteristics of the tube 40 55 V3 as a second limiter are concerned. Capacitor C_4 and resistor R_3 provide a filter network for the plate supply connections.

The tube V3 is an entrained or locked in oscillator. Its free oscillation frequency is determined by the tuned tank circuit comprising inductance L_3 and capacitor C_7 , this circuit being tuned to the center of the intermediate frequency band. The locked oscillator tube may be of the heptode type wherein the second and fourth grids, 45 i. e., the screen grid, serves as the plate of the oscillator, and the #3 grid serves as the oscillator control grid. Feedback voltage is obtained from inductance L_3 through inductance L_2 coupled thereto and fed to the #3 grid through coupling 50 capacitor C_6 . The resistor R_6 serves to prevent resonance in L_2 , and R_5 is the oscillator grid bias resistor. The locking or control signal is fed to the first grid GO from the anode of tube V2. Voltage of a frequency near the free or untrained oscillator frequency fed to the grid GO 55

does not vary the amplitude of the oscillations generated but serves to vary and control their frequency. The amount by which the frequency of the oscillator may be varied is determined by the amplitude of the signal applied to the grid GO, that is to say, the variation in frequency inherent in the received signal may vary the oscillator frequency to an extent proportional to the amplitude of the received signal fed from the limiter tube V2. In a practical embodiment .5 volt I. F. fed to the oscillator V3 held it entrained or in locked condition over a frequency swing of 3000 cycles, while approximately .25 I. F. volt alternating current will hold it entrained or locked in for only 1500 cycles. Obviously in either case the oscillator is entrained over a band of frequencies sufficient for use in a frequency shift signalling system where the frequency shift FS may be of the order of several hundred to several thousand cycles. Of course the amplitude of the entraining signal supplied to the grid GO of the tube V3 is constant for a given setting of the potentiometer point on R2, hence R2 serves as a control on the locked-in range and consequently a selectivity control. The output of the locked oscillator which follows the frequency of the limited frequency shift currents fed to the grid GO of tube V3 is impressed on a discriminator and detector of a modified Seeley type. This discriminator and detector includes a transformer T3 having a parallel tuned primary including inductance L4 and capacitor C8 and a parallel tuned secondary including inductance L6 and capacitors C10 and C11 and a pair of diodes differentially connected by the secondary winding L6, and also coupled in like phase or in parallel by the lead 30. The operation of this discriminator and detector is well known in the art, and will not be described further at this point. The output may be taken between one cathode and ground and used as desired and as described hereinafter.

An important factor in the operation of such a limiter-locked oscillator circuit is its operation in the presence of random noise voltages. Operating under the conditions described above, i. e., below saturation of the control signal applied to grid GO, see Fig. 5a, the frequency of the locked oscillator will tend to return to its free oscillation frequency in the absence of a discrete frequency signal voltage. This disengagement of the oscillator from the influence of the control voltage, when the same disappears or becomes too low, has been called its "breakout characteristic." For a signal consisting of a random distribution of frequencies with random amplitudes the oscillator will generally lock to those frequencies nearest its free oscillation frequency because its lock-in sensitivity is greatest at its free oscillation frequency, see Fig. 5b. This is the case when the current limiter tube V2 is saturated by a voltage having a frequency outside the lock-in range of the oscillator and also when the signal is absent due to fading. This is very significant when it is applied to the weaker (instantaneously) of the mark or space frequencies during selective fading. It reduces the noise voltage developed from the usual wide frequency swings in the absence of signal, and thereby prevents the teletype character from being destroyed.

The limiter-locked oscillator serves to improve reception in the following manner. Fig. 6a shows a keyed signal which, when transmitted by frequency shift methods, is received at the output of the receiver limiter as shown in Fig. 6b. Points

X, Y and Z represent the frequency of voltages greater than the signal which has saturated the limiter at these times. The frequency of the locked oscillator is shown in Fig. 6c. It will be noted that at times X, Y and Z the oscillator has returned to zero frequency deviation (its free oscillation frequency) because the control signal frequency (6b) has swung beyond the lock-in range (shown dotted in Fig. 6c). As is shown in Fig. 6d, these interference bursts have no effect on the signal because a voltage swing of $\frac{2}{3}$ to $\frac{3}{4}$ of the peak-to-peak signal voltage (depending on setting of threshold control) is required to trip the locking circuit 18 Fig. 3. It is clear that if the interference pulse fully saturates the limiter outside the lock-in range of the oscillator there will be practically no lock-in voltage at the required lock-in frequencies and the oscillator will "break-out" and return to its free oscillating frequency. However, even in the event that the interference pulse is barely greater in amplitude than the signal, thus producing a random distribution of frequencies inside the lock-in range, the oscillator will tend to lock to frequencies nearest its free oscillation frequency in view of its lock-in sensitivity characteristic (see Fig. 5b). Similarly, at a time when the signal fades into the noise and mainly a random distribution of noise voltage is left the oscillator will exert a form of selectivity on the noise and limit the swing of the noise voltages. This characteristic is important when selective fading is present.

Fig. 7a shows a received signal from a keyed waveform as in Fig. 6a. It will be noted that the mark signal at U and W and the space signal at V have faded into the noise. This may occur during frequency selective fading. The tendency of the oscillator to lock to those frequencies near its free oscillation frequency is shown in Fig. 7b. Here U, V and W show much smaller frequency excursions. In fact in these particular cases the conditions are such that the original signal is restored (Fig. 7c) at the output from the locking circuit.

An attempt has been made to show, in the foregoing paragraphs, that a signal may be restored even though it has undergone unfavorable propagation and reception conditions. However, it is important to note that interference and noise of the type shown in Figs. 6b and 7a will practically always destroy the pulse following it as well unless means are employed to reduce the frequency excursion, and consequent detected D. C. voltage change, involved.

It will be noticed that these advantages stem largely from the "break-out" characteristics of a locked-in oscillator. An examination of this characteristic in lock-in oscillators seems to indicate that the best mode of operation occurs when the oscillator is locked at its fundamental frequency.

In Fig. 8 I have illustrated the essential features of a frequency shift receiving system arranged in accordance with my invention which proved very satisfactory in operation. In this figure I have omitted the radio frequency amplifiers, converters, etc., and it is assumed that frequency shifted energy of intermediate frequency of about 400 kc. $\pm$ FS is impressed on the input of transformer T1. The limiter including tube V2, the locked-in oscillator including tube V3 and the discriminator and detector including the diodes V4 operate substantially as described above to supply keyed pulse energy to the reversing switch RS. The frequency shift modulation in the embodiment being described may total about 850 cycles. Circuits T3

and T4 are tuned to the intermediate frequency which may be say 400 kc. It is, of course, possible to operate the locked oscillator including circuits T3 and T4 at a sub-harmonic of the intermediate or fundamental frequency. Preferably the oscillator is locked-in at the fundamental because at F/n there are many combination frequencies at which random noise may lock, whereas at F random noise tends to lock very near to the free oscillator frequency.

The circuit including condenser C14 and inductance L13 is parallel tuned to the intermediate frequency and serves as an impedance across which the IF voltage is developed by the intermediate frequency amplifier tube V1. Resistor R13 and condenser C16 serve as a plate supply filter. The voltage developed across condenser C14 and inductance L13 is impressed by coupling condenser C15 on the first grid GL of the limiter tube V2 which as in the prior embodiment operates as a conventional grid plate limiter. Condenser C15 and resistor R14 provide a short time constant grid input circuit. Condenser C19 and resistor R16 provide a lower than normal screen grid voltage thereby establishing the proper operating conditions for the current amplitude limiting action in tube V2 which is as in Fig. 4.

Intermediate frequency voltage limited in tube V2 appears across the resistor R20 and resistor R22 for the broad selectivity position of switch S, and across resistor R20 and resistor R21, with resistor R22 in parallel in the sharp selectivity position. The resistor R24 and condenser C19' serve as a plate supply filter. Resistors R20, R22 and R21 serve as a form of potentiometer by which a portion of the IF voltage from tube V2 is fed through condenser C20 to the grid of V3. With switch S in the broad selectivity position that portion of the IF voltage developed across R22 is used, while a smaller portion of the voltage that is developed across the resistors R21 and R22 in parallel is used, when switch S is in the sharp selectivity position. Condenser C20 and resistor R24' provide a short time constant grid input circuit insofar as the operation of the tube V3 as a second limiter is concerned. Selectivity, improved over that which occurs in the known receivers, i. e., which do not have my locked-in oscillator, occurs by virtue of the combination of the current limiting stage including tube V2 and the locked-in oscillator stage including tube V3. Operation of the locked-in oscillator is similar in some respects to that described by G. L. Beers in his U. S. Patent #2,356,201, dated August 22, 1944. See also page 730 of the IRE of December 1944. It is noted, however, that here the oscillation is locked-in at the fundamental frequency rather than at a subharmonic thereof as in Beers. The amplitude of the IF voltage fed from the limiter stage including tube V2 to the locked oscillator tube V3 is just sufficient to provide a locking range of 3000 cycles in the broad selectivity position of switch S, and 1500 cycles in the sharp selectivity position. In the embodiment tested .5 volt and .25 volt were used for the broad and sharp selectivity positions respectively. Interference voltages at frequencies outside the locking range and having amplitude sufficient to saturate the limiter caused a break-out characteristic similar to that described by Beers. Advantage is taken here of the fact that such break-out does not generally cause distortion of a teletypewriter signal. This is because the change in voltage during break-out is only one-half the mark to space

change developed by the wanted signal, while two-thirds of the mark to space voltage change is required to trip the first locking circuit LC including tubes V6 and V1.

5 In the operation of this equipment, for reasons given above, it is important that the IF voltage at the grid of limiter tube V2 due to the weaker of the two frequencies ($F \pm F_s$) be 5 volts or greater to insure saturation of the limiter at all times. A grid voltage at tube V2 of 20 to 30 volts (IF noise) when the receiver antenna circuit is short-circuited has been found desirable for best operation. It is evident that tube V2 may also be a locked oscillator limiter if circuit conditions 10 warrant.

15 The locked-in circuit is otherwise substantially as illustrated in Fig. 4, the transformer T3 comprising a winding L19 in the third grid circuit and a winding L15 between the screen grid of tube V3 and the potential source +B3. Voltage dropping resistors R28 and R29 are included in the last connection. A bypass condenser C24 completes the radio frequency circuit. The circuit including condenser C26 and inductance L19 are parallel tuned to the fundamental or IF frequency. This circuit is shunted by biasing and damping resistor R30 and coupled by condenser C29 to the third grid of tube V3. The anode, which is electronically coupled to the oscillation electrodes and circuits, feeds the frequency shifted oscillations to the frequency discriminator network T4, which needs no further explanation.

20 The purpose of the switch RS is to permit reversal of the output of the diode detectors V4 in the event it is desired to change the relation between mark and space frequencies and the detector output pulse magnitude representing mark and space for any reason. The tuning meter M is also arranged to be connected across the output of the diodes V4 in either position of RS for tuning purposes. The output is fed by a large condenser C12 (Fig. 3 also), and potentiometer R40 to an amplifier 40 and from the amplifier 40 to a keying speed selecting switch KS through the 25 large condenser C17 (Fig. 3 also) and resistor R46 to tube V6 in a first locking tube circuit LC. The low pass filter LF may be omitted when the keying speed is high.

30 The locking tube circuit LC comprises, as is well known in the art, a pair of electron discharge devices V6 and V1 so arranged that when one draws current the other is cut off and vice versa. In the embodiment illustrated the control potential is applied to the first grid of the tube V6 and this tube is non-conductive in marking condition. The tube V1 is conductive in marking condition and non-conductive on space. The discriminator and detector detects the frequency shifts and supplies pulses of direct current to condenser C17 which vary between mark condition, wherein they are sufficiently negative to cut off current in tube V6, to space condition, wherein they are sufficiently positive to cause current to flow in tube V6.

35 The anode of the tube V6 is coupled to the grid of a tube V10 in a second output locking or tripping circuit LC' including another tube V11. The arrangement here is as disclosed in Cohoon U. S. application Serial #649,343, filed February 21, 1946. The current flow through V10 passes through resistance R51 so that the grid of tube V11 connected to R51 by resistance R52 becomes more negative when V10 draws current. The 40 current through tube V11 and resistance R58

serves in the same way to bias the grid of tube V10 through resistance R71 when V11 draws current.

In the sake of simplicity the locking circuit LC' here is shown in the polar connection so that the current flow iV10 through the tube V10 is from plus B1 through the tube impedance to ground and from ground through the relay connected to the terminals a, e of the receptacle 69, through the filter F, the meter M1, and through resistor R51 to the negative terminal of source B1. Current flow through the tube V11 passes through the teletypewriter relay in the opposite direction. This path for the tube V11 current iV11 is from plus B2 through the tube V11, through the meter M1, the filter F, the teletypewriter relay winding to ground and from ground back to the resistor R58 to the negative terminal of source B2. In this manner the teletypewriter relay is operated and the signal is recorded. The variable resistance R61 is in shunt to the teletypewriter relay and serves as a means to vary the current therethrough in polar connection as shown. In the neutral position not shown it is in series with the teletypewriter relay. Resistor R66 is included in the absence of resistance in the external line (connected at a and e) to damp the teletypewriter relay coil. Meter M1 measures the teletypewriter current. The filter F reduces the radiated noise voltages from steep wave fronts of the output current and also prevents internal pick-up of voltage from strong external fields in the vicinity of the equipment.

In operation the potential at the negative end of resistor R58 is minus substantially 60 volts when the tube V11 is conductive. This tube conducts on space and this negative potential may be used through lead 69 to operate a tone keyer including tube V13 and tone source 74. When the tube V11 is conductive current flows through the resistance R58 to make the end thereof adjacent source -B2 highly negative. This condition takes place on space and the highly negative potential on the third or suppressor grid of tube V13 makes the same non-conductive so that no tone is supplied through the tube V13 and tone transformer 60' to the outgoing line plugged into the receptacle at c and d. When the tube V11 is cut off as it is during mark no current flows through R58 and the potential at the upper end thereof assumes about ground potential. The third grid of tube V13 becomes less negative and this tube is adjusted and so excited that it now passes tone to the outgoing line. Thus we have keyed tone output, a pulse of which is present during marking condition and blocked off during spacing condition.

Since in the embodiment described tube V6 is switched to be non-conductive in the mark condition, its anode potential then goes up as does the potential on the grid of tube V10 and tube V10 is conductive in the mark condition. This turns tube V11 off in mark condition.

In the embodiment described the following type tubes are used. V1 is a 6SG7; V2 is a 6SJ7; V3 is a 6SA7; V4 is a 6H6; V6 and V7 are 6SJ7's; and V10 and V11 are 6L6GA's.

In the embodiment described the messages start on "space" and terminate on "mark." If the signal carrier drops out or is not being transmitted, i. e., between messages, the locking circuit may be left in the space condition and no tone output will be supplied.

I provide an improved circuit set in operation in the absence of carrier energy for setting up in

one of the tubes of one of the locking circuits the condition at which said tube would operate on the reception of marking signals. Then the teletypewriter will be receiving mark output current and the tone keyer V13 will be conductive to supply tone output when no signal is being received. To do this I connect the plate of tube V9 through a resistor R70 to the anode of tube V7 and screen grid of tube V6. Thus the tubes V7 and V9 have their anodes supplied by direct current potential through the same resistor R74 from the same source. The resistor R70 is a current limiting resistor. As pointed out hereinbefore the tube V7 conducts during reception of a mark signal. The operation of the tubes V6 and V7 is such that their anode voltages are approximately 20 volts when the tubes are conducting and 120 volts when the tubes are non-conducting. A reduction in the plate voltage of one tube causes it to conduct because this reduction serves to cut off the plate current in the other tube by lowering its screen grid voltage when bias existing across the cathode resistor R72 is considered. Cutting off the plate current of the second tube causes its plate voltage to rise which increases the screen voltage on the first tube and allows the first tube to conduct. This is fundamental in locking circuits of this type. Under normal signal conditions transition or flipping of current between the tubes occurs when a voltage is applied to the grid of the first tube, in this case, tube V6. Hence if the tube V9 is caused to draw plate current through resistor R74 (at the anode of tube V7) the plate voltage of the tube V7 will be reduced and V7 will become the conducting tube and the output current of the equipment will be on mark, that is, the tube V7 will draw current as it does during signaling in the mark condition. Tube V11 will then be cut off as it is in the mark condition.

The screen grid of tube V9 is fixed at approximately 90 volts and is supplied by resistors R78, R79 and R80. If a bias of -6 volts or more is applied to the control grid of tube V9 it is essentially non-conductive and has no effect on the tubes V6 and V7, that is, it does not lower the potential on the anode of the tube V7. However, if minus 4 volts or less is supplied to the control grid of tube V9 it becomes conductive and draws plate current through resistor R74. This drop in potential at the anode of tube V7 causes the tube to become conductive, in which case it is in the mark condition to supply output current to the teletypewriter and tone to the keyed line. A bias which is a function of the signal strength is supplied to the grid of tube V9 from the grid GL of the current amplitude limiter tube V2. Rectified signal current flowing in the grid circuit of tube V2 develops a voltage, depending on the current intensity, which appears across grid resistor R74 in the conventional operation of this limiter. This rectified voltage which is negative at the grid GL is reduced approximately 10 to 1 by resistors R15, R81 and R83, and is fed to the grid of tube V9 through an RC filter including resistor R84 and condenser C60. Condenser C51 serves as an IF filter. The RC filter including resistor R84 and condenser C60 serves to remove unwanted audio components from the bias developed on the grid of tube V9 and also to prevent instantaneous high amplitude noise peaks from being applied to this grid. The time constant of this circuit is approximately .2 second. The combination of resistors R15, R81 and R83 also serves to isolate the slow time constant circuit R84 and

condenser C60 from the grid of tube V2. As the IF signal on the grid of tube V2 is generally much greater than 60 volts peak, and therefore produces a D. C. potential of the same order of magnitude, it can be seen that tube V9 is cut off and has no effect during normal reception of signals. This is because

$$\frac{R83}{R15 + R81 + R83} = \frac{1}{10}$$

and at least 6 volts (minus) D. C. is applied to the grid of V9. However, when a wanted carrier is not being received the voltage on the grid of V2 is generally less than 40 volts peak and consequently tube V9 is conducting and the output current from the equipment is mark. Variations in the values of the resistors R15, R81 and R83 can be made to accommodate different IF voltages than those mentioned. This mark maintaining circuit is necessary in the absence of received signals, as otherwise the teletypewriter will print gibberish from the presence of noise impulses generated in the system which operate the locking circuits. The tube V9 is of the 6SJ7 type.

What is claimed is:

1. In apparatus for demodulating electrical energy which is shifted in frequency between two frequencies separated by a band of frequencies, to derive direct current voltages which vary between two values as said frequency is shifted, for operating a locking circuit controlling a recorder, said locking circuit including two electron control devices one of which is to be conductive in response to the presence in the apparatus of electrical energy of one frequency and the other of which is to be conductive in response to the presence in the apparatus of electrical energy of the other frequency, a regenerative oscillation generator of variable frequency, an electron control device current amplitude limiter excited at its input by said electrical energy and having an output circuit, a coupling between the output circuit of the current amplitude limiter and the oscillation generator for entraining the generator in accordance with the limiter output, a frequency discriminator and detector having a frequency variation versus voltage characteristic which is linear over a frequency range greater than said first mentioned band coupled to the output of said generator, and means for applying the output of the detector to said locking circuit to operate the same and control said recorder.

2. In a signaling system in combination, a locking circuit including two electron control devices one of which is to be conductive in one signaling condition, a current amplitude limiter excited by currents modulated in frequency in accordance with signals from said one signaling condition to another signaling condition, signal current amplifying and detecting means coupling said current amplitude limiter to said locking circuit for controlling the same to make said one device conductive in said one signaling condition, and a second coupling between said limiter and said locking circuit for making said one device conductive in the absence of said modulated currents at the current amplitude limiter.

3. In a frequency shift telegraphy system including a locking circuit having one electron control device which is non-conductive in signal marking condition, a current amplitude limiter having an input excited by high frequency currents shifted in frequency between one frequency representing "mark" and another frequency representing "space," an oscillation generator having an output circuit tuned to a frequency integrally

related to the mean frequency of said frequency shifted currents, means for entraining said generator by the output of said current amplitude limiter, a discriminator and detector having its input excited by the output of said generator, said detector supplying as output a direct current component which varies between two values, one representing "mark" and the other "space," a coupling between said detector output and said locking circuit such that said one device is rendered non-conductive by appearance of a direct current potential in the output of said detector representing "mark," and a coupling between the current amplitude limiter and said locking circuit such that said one device is non-conductive in the absence of input to said current amplitude limiter.

4. In a frequency shift telegraphy system including a two-electron-control device locking circuit having one device which is biased to cutoff in signal marking condition, a current amplitude limiter electrode structure having an input excited by high frequency currents shifted in frequency between one frequency representing "mark" and another frequency representing "space," said limiter structure having electrodes in a biasing circuit wherein is developed a potential of a magnitude depending on the strength of the high frequency currents, an oscillation generator having an output circuit tuned to the mean frequency of said frequency shifted currents, means for entraining said generator by the output of said current amplitude limiter, a discriminator and detector having its input excited by the output of said generator, said detector having as output a direct current component which varies between two values, one representing "mark" and the other "space," a coupling between said detector output and said locking circuit such that said one device is rendered non-conductive by appearance of a direct current potential in the output of said detector representing marking condition, and a coupling electron control device between said biasing circuit of said current amplitude limiter and said locking circuit for biasing said one device thereof to cutoff in the absence of input to said current amplitude limiter.

5. In a telegraphy system in combination, signal recording apparatus including a locking circuit having two electrode structures with their electrodes so coupled that when current flows in one structure current is cut off in the other structure and vice versa, a current amplitude limiter electrode structure having input electrodes excited by telegraphy currents keyed between two conditions, one representing "mark" and the other representing "space," said current amplitude limiter having in a biasing circuit therefor an impedance the potential drop of which depends upon the magnitude of the telegraphy currents, detecting means having an input coupled to said current amplitude limiter output, a coupling between the output of said detecting means and the control electrode of a structure in said locking circuit for tripping the same to one condition of stability in the presence of telegraphy currents representing "mark," and a coupling electron control device between the impedance in said limiter biasing circuit and an electrode in one of said structures in said locking circuit to trip the same to said one condition of stability in the absence of telegraphy signals at the input of said limiter.

J. C. E. MITCHELL.
